UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

COMPOSITE METAL-AND-WOOD TIE FOR RAILWAY-TRACKS.

No. 838,572.

Specification of Letters Patent.

Patented Dec. 18, 1906.

Application filed August 2, 1906. Serial No. 328,826.

To all whom it may concern:

Be it known that I, JOHN F. O'CONNOR, a citizen of the United States, residing in Chicago, in the county of Cook and State of Illinois, have invented a new and useful Improvement in Composite Metal-and-Wood Ties for Railway-Tracks, of which the following is a specification.

My invention relates to ties for railway-tracks.

The object of my invention is to provide a composite tie of wood and metal for railway-tracks of a strong, simple, efficient, and durable construction capable of being cheaply manufactured, which will unite in itself the cushioning advantages of the ordinary wooden tie and the strength and durability of the metal tie, which will have adequate provision for shrinkage or swelling of the wood members under variations in moisture without interfering with the snug coöoperative relation of the wood and metal members, and by means of which a railway-track may be rapidly and conveniently laid, repaired, or replaced with little labor and expense, and by means of which side pressure of the train upon the rails will come diagonally upon the wood members.

My invention consists in the means I employ to practically accomplish this object or result—that is to say, it consists in a composite wood-and-metal railway-track tie comprising in coöperative combination a metal tie member extending between the rails and having at each end an enlarged base provided with a wedging angular or flaring socket with upright ends formed by transverse shoulders or flanges on the base portion, diagonally-arranged wood blocks fitting in said flaring sockets, and metal rail-seat or cap members having angular wedging or flaring sockets fitting and resting upon the wood blocks which fit between the upright shoulders or flanges of the enlarged bases of the metal tie member and provided with integral lips or hooks for securing the track-rails thereto, the sockets in the bases of the metal tie member being upwardly inclined, so that the wood blocks keep a slightly-inclined position, thus causing the lateral thrust of the train upon the rails to come diagonally upon the wood blocks.

My invention also consists in the novel construction of parts and devices and in the novel combinations of parts and devices herein shown and described.

In the accompanying drawings, forming a part of this specification, Figure 1 is an elevation of a railway-track tie embodying my invention, showing the track-rails in section. Fig. 2 is a plan view. Figs. 3 and 4 are cross-sections of the tie on lines 3 3 and 4 4, respectively, of Fig. 1; and Fig. 5 is a longitudinal section through the base portion of the tie at one end thereof on line 5 5 of Fig. 2.

In the drawings, A represents the rails of a railway-track, and B the metal tie member extending between the rails and provided at each end with enlarged bases B' B', having flaring or wedging and upwardly-inclined sockets B² to receive the diagonally-arranged and upwardly-inclined wood blocks C. Each of the enlarged bases B' is provided with transverse shoulders or flanges b, extending at right angles to the sockets and forming the ends of the sockets B² and serving as shoulders or end abutments for the ends of the diagonally-arranged and upwardly-inclined wood blocks C to abut against to hold the same in place longitudinally of the tie. The diagonally-arranged and upwardly-inclined wood blocks C are preferably square in cross-section, and the two lower sides of each of these blocks fit snugly against the inclined or flaring lateral walls b' of the sockets B².

D are the rail-seat or cap members, on which the rails A directly rest and which themselves rest directly upon the diagonally-arranged and upwardly-inclined wood blocks C and which are interposed between the upwardly-inclined rail-seat or cap members D and the enlarged bases B' of the metal tie member B. The rail-seat or cap members D are each furnished with wedging or flaring and upwardly-inclined sockets D' on the under sides, the inclined or flaring walls d of which fit snugly against the two upper faces of the diagonally-arranged and upwardly-inclined wood blocks C. The rail-seat or cap members D engage at their ends the wood blocks C, which fit between the transverse flanges or shoulders b b of the bases B', thus holding the members D snugly in place longitudinally of the tie.

The interposed diagonally-arranged and upwardly-inclined wood blocks C C separate the seat or cap members D and bases B' from each other sufficiently to allow for all shrinkage of the wood blocks, so that the rails may have the full cushioning effect of the interposed wood blocks. The wood blocks at the same time serve not only as cushioning members, but also as a means for locking or holding the metal tie member B and the rail-seat or cap members D D together.

The upwardly-inclined rail-seat or cap members D are furnished with horizontal ledges or sides D² to receive the rails and with integral flanges or lips d' d', arranged diagonally at opposite edges of the side D² and adapted to engage and embrace the opposite flanges a a of the rail A. The free space or opening d² between the rail locking or engaging lips d' d' equals the width of the flange-base of the rail, so that by turning the rail-seat or cap member D at an angle to the rail A it may be applied to the rail and then caused to snugly embrace the flanges of the rail by simply again turning the seat or cap member D at right angles to the rail. The rail-seat or cap members D may preferably be made of malleable or tough metal, so that the rail holding or locking lips d' d' may, if desired or when required, be hammered down tightly upon the flanges of the rail. The rail-seat or cap members D D are provided with end flanges or shoulders d³ to engage the ends of the diagonally-arranged and upwardly-inclined wood blocks C, which fit within the transverse flanges or shoulders b of the bases B'. By combining with the other parts upwardly-inclined wood blocks and making the sockets in the enlarged bases of the tie member and in the cap members correspondingly upwardly inclined the lateral or horizontal thrust of the train upon the rails is caused to come somewhat diagonally across the short wood blocks C, and thus prevents any danger of the rails spreading by splitting the wood blocks. The angle at which the wood blocks are upwardly inclined may be varied according to requirements. Ordinarily a slight angle is sufficient.

The metal tie members B are preferably provided with an integral supplemental socket B⁴ to receive an insulating-block C', of wood or other electrically-insulating material, and which serves as an end abutment for the rail-seat or cap member D at the inner end thereof. The rails A A are thus electrically insulated from each other, so that either one or both rails may be used as part of an electric circuit when desired.

I claim—

1. In a railway-track, the combination of the track-rails with a composite metal-and-wood tie comprising a metal tie member extending between the rails and provided with

enlarged bases at each end thereof, having 65 wedging or flaring and upwardly-inclined sockets to receive wood-block members and transverse flanges or shoulders for the ends of the wood-block members to abut against, diagonally-arranged and upwardly-inclined 70 wood blocks fitting in said sockets, and rail-seat or cap members having sockets on their under faces fitting the interposed wood blocks, substantially as specified.

2. In a railway-track, the combination of 75 the track-rails with a composite metal-and-wood tie comprising a metal tie member extending between the rails and provided with enlarged bases at each end thereof, having 80 wedging or flaring and upwardly-inclined sockets to receive wood-block members and transverse flanges or shoulders for the ends of the wood-block members to abut against, diagonally-arranged and upwardly-inclined 85 wood blocks fitting in said sockets, and rail-seat or cap members having sockets on their under faces fitting the interposed wood blocks, said rail-seat or cap members having integral locking-lips engaging the flanges of 90 the rails, substantially as specified.

3. In a railway-track, the combination of 95 the track-rails with a composite metal-and-wood tie comprising a metal tie member extending between the rails and provided with enlarged bases at each end thereof, having 100 wedging or flaring and upwardly-inclined sockets to receive wood-block members and transverse flanges or shoulders for the ends of the wood-block members to abut against, diagonally-arranged and upwardly-inclined 105 wood blocks fitting in said sockets, and rail-seat or cap members having sockets on their under faces fitting the interposed wood blocks, said rail-seat or cap members having integral locking-lips engaging the flanges of 110 the rails, said locking-lips being diagonally arranged in respect to each other at the opposite edges of the rail-seat or cap member with an open space between them to receive the flanges of the rail when the cap member is 115 turned at an angle to the rail, substantially as specified.

4. A composite metal-and-wood railway-tie comprising a metallic tie member provided with bases at each end having wedging or 115 flaring and upwardly-inclined sockets to receive wood blocks, rail-seat or cap members having wedging or flaring sockets to receive wood-blocks, and upwardly-inclined wood blocks interposed between and separating 120 said metal tie member and said rail-seat or cap members, substantially as specified.

5. A composite metal-and-wood railway-tie comprising a metallic tie member provided with bases at each end having wedging or 125 flaring and upwardly-inclined sockets to receive wood blocks, rail-seat or cap members having wedging or flaring sockets to re-

ceive wood blocks, upwardly-inclined wood blocks interposed between and separating said metal tie member and said rail-seat or cap members, said metal tie members being 5 provided with transversely-extending shoulders or flanges to form end abutments for the wood blocks, substantially as specified.

6. A composite metal-and-wood railway tie comprising a metallic tie member provided with bases at each end having wedging or flaring and upwardly-inclined sockets to receive wood blocks, rail-seat or cap members having wedging or flaring sockets to receive 10 wood blocks, upwardly-inclined wood blocks interposed between and separating said metal tie member and said rail-seat or cap members, said metal tie member being provided with transversely-extending shoulders or flanges to form end abutments for the 15 wood blocks, said rail-seat or cap members having flanges abutting against said wood blocks, substantially as specified.

7. A composite metal-and-wood railway tie comprising a metallic tie member provided with bases at each end and having 25 wedging or flaring and upwardly-inclined sockets to receive wood blocks, rail-seat or cap members having wedging or flaring sockets to receive wood blocks, upwardly-inclined wood blocks interposed between and separating said metal tie member and said rail-seat or cap members, said metal tie members being provided with transversely-extending shoulders or flanges to form end abutments for the wood blocks and with supplemental sockets to receive insulating-blocks 30 for the inner ends of said rail-seat or cap members D to abut against, substantially as specified.
